DISPLAY RACK

Donald W. Treimann, Neenah, Wis., assignor to Kimberly-Clark Corporation, Neenah, Wis., a corporation of Delaware

Filed Aug. 27, 1964, Ser. No. 81,479

Term of patent 14 years

(Cl. D80—9)

I claim:

The ornamental design for a display rack, as shown.
